ADJUSTABLE SNAP GAUGE

Filed June 7, 1946

UNITED STATES PATENT OFFICE

2,545,757

ADJUSTABLE SNAP GAUGE

Francis A. Barr, Laurelton, N. Y.

Application June 7, 1946, Serial No. 675,056

1 Claim. (Cl. 33—168)

1

This invention relates to a vernier gage and it is one object to provide a gage by means of which micrometer measurements may be taken, the gage having arms shiftable to adjusted positions and provided with blocks or buttons for engaging work straddled by the gage when the gage is in use.

Another object of the invention is to provide a gage having a first arm and a pair of second and third arms shiftable towards and away from the first arm, the second arm being longer than the third arm and so mounted that the second and third arms may be adjusted independent of each other.

Another object of the invention is to provide a gage having first, second and third arms with the second and third arms carrying blocks, one constituting a "go" block or button and the other constituting a "no go" button.

Another object of the invention is to provide a gage wherein the first, second and third arms have shanks shiftable longitudinally of each other to adjusted positions, the shanks of the second and third arms being provided with scale marks and the shank of the first arm being also provided with scales companion to the scales of the second and third arms, and allowing very accurate measurements to be obtained.

Another object of the invention is to provide a gage consisting of elements formed of hard metal and very simple in construction.

The invention is illustrated in the accompanying drawings wherein:

Figure 1 is a side view of the improved gage;

Figure 2 is a top plan view thereof;

Figure 3 is a rear view of the gage;

Figure 4 is a fragmentary sectional view taken along line 4—4 of Figure 1;

Figure 5 is a perspective view of a block or button carried by the second arm of the gage.

This improved gage is substantially C-shaped when viewed from a side and has a first arm 1 and second and third arms 2 and 3. A shank 4 extends from the rear or inner end of the first arm and has opposite side faces formed with longitudinally extending grooves or tracks 5 which are undercut along their side edges, as shown in Figures 2 and 4. Shanks 6 and 7 extend from the rear ends of the second and third arms and are formed with ribs 8 and 9 which fit into the undercut side edge portions of the grooves or tracks 5 to allow sliding adjustment of the shanks 6 and 7 longitudinally of the shank 4 but prevent lateral displacement of the same from the grooves. Flanges 10 project laterally

2

from the shank 4 along rear side edges of the grooves or tracks 5 and these flanges carry plates 11 which are secured by screws 12 and project partially across the outer side faces of the shanks 6 and 7. Screws 13 which are screwed into sockets formed in the shank 4 pass through slots 14 formed longitudinally of the shanks 6 and 7 and when the screws are tightened their heads bear against the outer side faces of the shanks 6 and 7 and firmly hold the second and third arms in adjusted positions. Each shank 6 and 7 is provided along its outer side face with a scale 15 which in the present illustration is four inches long and divided into inches and hundredths of an inch and each plate 11 is also provided with a scale 16 divided into thousandths of an inch, it being understood that the scales may be marked to provide any selected fractions of an inch.

Rear end portions of the second and third arms 20 are outwardly offset so that their shanks may extend along opposite sides of the shank 4 of the first arm and on the front ends of the second and third arms are formed heads 17 and 18 which are of such thickness that the head 17 has its 25 side face flush with the outer side face of the third arm 3 and the head 18 bears against the inner side face of the second arm 2, as shown in Figure 2. Grooves 19 and 20 are formed in the heads of the second and third arms and into 30 these grooves are fitted blocks or buttons 21 and 22. The "go" button 21 and the "no go" button 22 are of duplicate construction and each is formed with a longitudinally extending slot 23 and a longitudinally extending recess 24 to accommodate the heads of screws 25 which pass 35 through the slots 23 and into sockets formed in the heads 17 and 18. When the screws 25 are tightened the buttons will be held in adjusted positions and when the screws are loosened the buttons may be slid longitudinally to positions in which they project from under faces of the second and third arms desired distances. Set screws 26 are threaded through openings 27 formed vertically through the forward ends of 40 the second and third arms and by turning these screws they may be brought into engagement with upper ends of the blocks or buttons and limit upward movement of the blocks. The front end portion of the first arm is formed with a recess 28 into which fits a block or button 29 45 formed with threaded sockets 30 to receive screws 31 which are passed upwardly through the arm and serve to hold the block 29 in place.

When the gage is in use the second and third arms are shifted with relation to the first arm

until a predetermined reading is obtained by the companion scales and the screws 13 tightened. The "go" and "no go" buttons are also set to cause button 21 to have its lower end spaced upwardly from the plane of the lower end of button 22 a predetermined distance and the gage disposed in straddling relation to the object to be measured as shown in Figure 1. Adjustment of the buttons 21 and 22 provides a predetermined tolerance.

Having thus described the invention what is claimed is:

A gage comprising an L-shaped first arm having an upwardly extending shank at one end thereof, second and third L-shaped arms each having a depending shank at one end thereof, the shanks of the second and third arms being disposed at opposite sides of the shank of the first arm and formed with longitudinally extending slots, the shank of the first arm having its opposed side faces formed with undercut grooves and the shanks of the second and third arms being slidably received in the grooves and having ribs along their side edges engaged in the undercut portions of the grooves to prevent lateral displacement of the shanks of the second and third arms from the grooves, screws passed through the slots and engaged in threaded sockets formed in the shank of the first arm and when tightened gripping the shanks of the second and third arms to hold the second and third arms in adjusted positions, flanges projecting outwardly along rear edges of the grooves, plates carried by said flanges and overlapping the side faces of the shanks of the second and

third arms, the plates and the shanks of the second and third arms having companion scales marked thereon, a block mounted in a recess formed in the end of the first arm remote from the shank, the second and third arms having their ends remote from their respective shanks formed with heads having recesses leading from their inner edge faces, blocks fitting in the recesses of the second and third arms and shiftable longitudinally therein and formed with longitudinally extending recesses and slots, and screws passing through the slots of the blocks and screwed into sockets in the second and third arms with their heads engaged in the recesses and gripping the blocks to hold them in set positions when tightened.
